CLAIM

The ornamental design for a boot liner, substantially as shown and described.

DESCRIPTION

FIG. 1 is a front perspective view of the boot liner.

FIG. 2 is a rear perspective view thereof.

FIG. 3 is a front elevation view thereof.

FIG. 4 is a rear elevation view thereof.

FIG. 5 is a left, front perspective view thereof in a closed position.

FIG. 6 is a rear perspective view thereof in a closed position.

FIG. 7 is a top plan view thereof in a closed position.

FIG. 8 is a bottom plan view thereof in a closed position.

FIG. 9 is a left side elevation view thereof in a closed position.

FIG. 10 additionally shows a foot depicted in dotted line, representing an environmental feature which is not a part of the claimed design.

FIG. 11 is a front elevation view thereof in a closed position; and,

FIG. 12 is a rear elevation view thereof in a closed position. The broken lines throughout the drawings represent portions of the boot liner—such as seams—that do not form part of the claimed design.

In all additional views, the longer-segmented dashed lines represent environmental features which are not claimed.
